UNITED STATES PATENT OFFICE

2,641,863

WHEELED TOY

John Pinkney Gowland, Santa Barbara, Calif.

Application October 27, 1950, Serial No. 192,475
In Great Britain October 29, 1949

4 Claims. (Cl. 46—99)

1

According to this invention, a toy has an articulated body which is adapted to rest or to be supported on the ground or some other supporting surface and which comprises two parts hinged together on a pivot which lies transversely of the body when the latter is in its normal resting or supported position, the toy also having a control device of the sheath-and-core type comprising a sheath attached at one end to one part of the body and a core passing through the sheath and attached at one end to the other part of the body, the other ends of the sheath and core being attached to relatively movable handle parts, actuation of which effects a relative longitudinal movement of the sheath and core to draw the two parts of the body pivotally towards each other and thus cause them to tilt and rise into a hump at their hinge. The toy may also incorporate one or more elements mounted on the body and attached to one or the other of the body parts so as to rise and fall with the body part to which the element is attached. If a plurality of such elements are provided, they may be all attached to one of the body parts or, alternatively, one or more may be attached to one body part and one or more to the other. Such element or elements may be pivotally or otherwise relatively freely attached, so that an element is capable of executing movements of its own when rising and falling with the body part to which it is attached. The toy may incorporate a sound-producing device or any other desired device, which is arranged to be actuated in response to the pivoting movement of the body parts.

Very amusing effects may be obtained by the rising and falling movements of the articulated body executed under operation and release of the control device, which effects may be enhanced by accompanying movements imparted to an attached element or elements as above described, and by accompanying operation of a sound-producing or other device as mentioned.

The invention is susceptible of embodiment in a variety of constructional forms, and is applicable especially, but not exclusively, to pull toys. In the application of the invention to pull toys, the control device is adapted to serve as a lead for hauling the toy, thus forming a combined lead and remote control device. Toys embodying the invention may be constructed, for example, as toy vehicles or other objects, or toy animals or other figures, of various kinds; and these may be provided with additional elements as above mentioned, in the form of toy figures represent-

2

ing a driver with or without a passenger or passengers in the case of a toy vehicle or the like, or a rider or riders in the case of a toy animal or the like.

Accordingly, although a particular embodiment is more fully described below and shown in detail in the accompanying drawings, this is but illustrative of the many possible embodiments that may be made, the mechanical features, combinations of elements and arrangements of parts which constitute the invention and the scope of the application of which will be indicated in the appended claims.

In the drawings,

15 Fig. 1 is a perspective view showing one embodiment of the invention constructed as a toy automobile.

Fig. 2 is a side view with parts shown in section, and

20 Fig. 3 is a view similar to Fig. 2 showing the toy in an actuated position.

The illustrative embodiment shown is constructed as a toy replica of a pioneer type of automobile and is fitted with a flexible remote control device by means of which mechanisms of the toy may be actuated to produce certain effects and actions as will presently be described, and also by means of which the automobile may be hauled as a pull toy, it being made possible, on the one hand, to produce the above noted actions and effects, and, on the other hand, to haul the toy, each independently of the other, or both simultaneously, as may be desired by the user. The toy may be of substantially all-plastic construction by extensive use of plastic mouldings and stampings for the various parts of the toy or, if desired, it may be constructed in any other suitable material or materials. Referring to the drawings, the toy automobile comprises a

35 body shell structure which consists of two parts, a front part generally denoted by 10 and a rear part generally denoted by 11. The front part 10 comprises a rigid shell, e. g., of moulded plastic construction, including the radiator 12, bonnet 13 and scuttle 14, and having fitted thereon mock lamps 15, which may be plastic mouldings, and a mock windshield 16 which may consist of a wire frame. The front part 10 is also provided with a pair of dummy front springs 17 carrying collars 18 in which is journaled the front axle 19 of a pair of front road wheels 20. Behind the scuttle 14 a dummy steering column 21, on which a dummy steering wheel 22 is fixed, is rigidly fixed by an integral or separate web block 50 portion 23 to the scuttle. The parts 21, 22 and

23 may all be plastic mouldings. The rear part 11 comprises a rigid shell, e. g., of moulded plastic construction, including the floor 24 of the driving compartment, a seat 25 and a dummy toolbox 26, and carries a pair of dummy rear springs 27 which, like springs 17, carry collars (not seen in the drawings) in which is journalled the rear axle 28 of a pair of rear road wheels 29. At each side of the toy, a combined running board and mudguard structure 30, e. g., of plastic construction, is attached to the floor 24 by brackets 31. Also attached to the rear part 11 is a dummy bulb horn 32. The front part 10 and rear part 11 are hinged together in the region of the base of the scuttle 14 by a transverse hinge pin 33 (or a pair of stubs) carried by the rear part 11 and entering apertured lugs 34 on the front part 10.

Attached to the front end of the front part 10 below the radiator 12, such as by fixture in a socket 35 formed in that front end, is the inner end of the sheath 36 of a flexible lead of the sheath-and-core type, such as a Bowden cable, the outer end of the sheath 36 being attached to any suitable form of handgrip member 37. The sheath 36 may consist, for example, of a close-wound wire coil. The core 38, which may be in the form of a wire or cord passing through the sheath 36, passes through an aperture behind the socket 35 and is attached at its inner end to a suitable anchorage, such as a depending apertured lug 39 on the underside of the rear part 11. At its outer end, the core 38 is attached to an actuating element 40 associated with the handgrip member 37. The member 37 and element 40 form an actuating handle of any suitable character. For example, as shown, the member 37 comprises a slotted sleeve 41 having the sheath 36 attached to it at one end and terminating at its other end in a thumb ring 42, and the element 40 consists of a crossbar extending transversely through and slidable longitudinally in the slot 43 in the sleeve 41, the latter having a longitudinal keyway (not seen in the drawings) in which a key on the crossbar 40 is slidably guided to retain the crossbar in the sleeve. With a user's thumb in the ring 42, the crossbar 40 can be engaged at opposite sides of the sleeve 41 by two fingers and pulled along the sleeve (as seen in Fig. 3) so as to pull the core 38 through the sheath 36 and thus cause the two parts 10 and 11 of the automobile body to fold and rise upwardly about their hinge 33, drawing the rear wheels 29 towards the front wheels 20, as seen in Fig. 3, the body being restored to its normal condition shown in Figs. 1 and 2 by gravity (assisted, if desired, by the provision of a suitable spring now shown) when the crossbar trigger 40 is released.

A toy figure 44 representing a driver of the automobile holding the steering wheel 22 has its arms 45 pinned as at 46 to the steering wheel so as to hinge the figure to the wheel 22, and in the normal condition of the toy as seen in Figs. 1 and 2 the figure 44 rests in a sitting position on the seat 25. When the body parts 10, 11 are humped by operation of the trigger 40, figure 44 is lifted by the rising seat 25, and with a sharp pull on the trigger the parts 10, 11 are caused to hump abruptly, producing a bucking action which has the effect of abruptly throwing the figure 44 upwards and causing it to execute amusing pivotal movement about its hinge attachment to the steering wheel. The action may be arranged so that the figure is

caused to leap up on to the seat 25, as shown in Fig. 3, and to drop back on to the seat when the trigger 40 is released. If desired, a second toy figure (not shown), representing a passenger, 5 may be provided normally sitting on the seat 25 beside the figure 44, and the second figure may also be pivotally attached at some convenient point to the front part 10 of the body, e. g., to the windshield 16, so that the second figure, 10 as well as the figure 44, will leap up when the automobile bucks and will drop back on to the seat when the trigger 40 is released.

As shown, the hollow bonnet 13 contains a sound-producing device in the form of a conventional bellows-type squeaker 47, and the rear body part 11 is provided with an extension bar or fork 48 which extends forwardly from the hinge 33 under the bonnet 13 to engage and press upwardly against the squeaker 47 and thereby compress its bellows, as shown in Fig. 3, and cause the squeaker to sound in imitation of the horn 32 honking when the automobile bucks by actuation of the trigger 40. The squeaker 47 may be supported on the extension bar or fork 48 and is 20 pressed upwardly by the latter against the inside top wall of the bonnet 13 when the squeaker is actuated.

A toothed wheel 49 is provided on the rear axle 28 so as to revolve therewith, and a flexible tongue 50, e. g., of metal or plastic, is mounted at one end under the rear body part 11 such that the free end of the tongue engages with the teeth of the toothed wheel 49 and thereby causes a clattering sound to be produced at the rear end of the automobile as it is pulled along on its road wheels.

It will be evident that numerous modifications of the described embodiment may be made without departing from the essence of the described action of the toy when actuated by the remote control device. For example, instead of, or in addition to, actuating a squeaker 47, the extension bar or fork 48 or a similar member may be adapted to close the circuit of a dry battery housed in the bonnet and wired for lighting electric bulbs fitted in some or all of the lamps 15. Again, if a second toy figure is provided, one of them may be attached to the front body part 10 and the other to the rear body part 11 so that the two figures leap in opposite directions when the automobile bucks. Of course, in addition or as an alternative to the extension member 48, a rearward extension may be provided on the front part 10 and arranged to actuate or control a device carried by the rear part 11 for producing some desired action or effect, a further action or effect may, for example, be arranged to be obtained by partial actuation of the trigger 40; for instance, a device for producing a sound in imitation of engine backfiring may be provided and arranged to be operated on pulling the trigger 40, say half-way, the described actions of the automobile bucking, the horn sounding and the driver leaping up being effected by pulling the trigger 40 all the way.

Toy animal or like figures, e. g., toy quadrupeds, having articulated bodies mounted on ground wheels and carrying a rider, may be constructed in analogous fashion to the embodiment described, so that the rider is thrown upwardly when the animal or like figure is caused to buck, by bumping of its body parts through actuation of the remote control device.

I claim:

1. A toy automobile comprising an articulated

automobile body having a front part supported on front road wheels and a rear part supported on rear road wheels, said front part including bonnet and scuttle portions of the automobile and a steering column fixed to the rear of said scuttle portion and carrying a steering wheel, said rear part including a driving seat, means hinging said body parts together about a transverse pivot disposed between said front and rear wheels in the vicinity of the base of said scuttle portion, and manual control means including relatively movable parts connected to said body parts respectively and extending from said body for relative movement to draw said body parts pivotally towards each other on their supporting wheels and thereby cause them to buck upwards at their hinge.

2. A toy automobile comprising an articulated automobile body having a front part supported on front road wheels and a rear part supported on rear road wheels, said front part including bonnet and scuttle portions of the automobile and a steering column fixed to the rear of said scuttle portion and carrying a steering wheel, said rear part including a driving seat, means hinging said body parts together about a transverse pivot disposed between said front and rear wheels in the vicinity of the base of said scuttle portion, and manual control means including relatively movable parts connected to said body parts respectively and extending from said body for relative movement to draw said body parts pivotally towards each other on their supporting wheels and thereby cause them to buck upwards at their hinge, and a concertina sound-producing device arranged between relatively movable portions of said two body parts such as to be squeezed between said portions and thereby caused to emit sound upon relative movement of said portions due to bucking movement of said body parts.

3. A toy automobile comprising an articulated automobile body having a front part supported on front road wheels and a rear part supported on rear road wheels, said front part including bonnet and scuttle portions of the automobile and a steering column fixed to the rear of said scuttle portion and carrying a steering wheel, said rear part including a driving seat, means hinging said body parts together about a transverse pivot disposed between said front and rear wheels in the vicinity of the base of said scuttle portion, and

manual control means including relatively movable parts connected to said body parts respectively and extending from said body for relative movement to draw said body parts pivotally towards each other on their supporting wheels and thereby cause them to buck upwards at their hinge, and a toy figure having arms pivotally attached to said steering wheel and normally reposing in a sitting position on said seat, whereby to be caused to leap off said seat and execute independent pivotal movement about said steering wheel under forces transmitted to said figure by bucking movement of said body parts.

4. A toy automobile comprising an articulated body having a front part supported on front road wheels and a rear part supported on rear road wheels, said front part including bonnet and scuttle portions of the automobile and a steering column fixed to the rear of said scuttle portion and carrying a steering wheel, said rear part including a driving seat, means hinging said body parts together about a transverse pivot disposed between said front and rear wheels in the vicinity of the base of said scuttle portion, and manual control means including relatively movable parts connected to said body parts respectively and extending from said body for relative movement to draw said body parts pivotally towards each other on their supporting wheels and thereby cause them to buck upwards at their hinge, a toothed rattle wheel on one of said body parts, means for rotatably driving said rattle wheel from a ground wheel of the toy, and a flexible tongue fixed at one end to said rear body part and engaging with its free end the toothed periphery of said rattle wheel for emitting a rattling sound when said rattle wheel is driven.

JOHN PINKNEY GOWLAND.
